United States Patent Office

Des. 202,859
Patented Nov. 9, 1965

202,859

WALLET OR SIMILAR ARTICLE

Morton Feder, 3828 W. Whitton Ave., Phoenix 19, Ariz.

Filed Oct. 13, 1964, Ser. No. 82,144

Term of patent 14 years

(Cl. D87—3)

FIG. 1.

FIG. 2.

FIG. 3.

FIG. 4.

A writing tool is indicated by means of broken lines in FIGURE 1 for illustrative purposes only.

I claim:

The ornamental design for a wallet or similar article, as shown and described.
